UNITED STATES PATENT OFFICE

161,140

PAIR OF SUNGLASSES OR SIMILAR ARTICLE

Jean R. Shrewsbury, New York, N. Y.

Application April 30, 1949, Serial No. 2,361

Term of patent 7 years

(Cl. D57—1)

To all whom it may concern:

Be it known that I, Jean R. Shrewsbury, a citizen of the United States, residing at New York, in the county of Kings and State of New York, have invented a new, original, and ornamental Design for a Pair of Sunglasses or Similar Article, of which the following is a specification, reference being had to the accompanying drawing, forming part thereof.

In the drawing

Fig. 1 is a front elevational view of a pair of sunglasses or similar article showing my new design;

Fig. 2 is a top plan view thereof.

Fig. 3 is a side elevational view thereof.

The essential features of my design for a pair of sunglasses reside in the parts shown in full lines, the outstanding feature being the specific

shape of the shield extending to the base of the circular area and having the ends pointed toward each other.

I claim:

The ornamental design for a pair of sunglasses or similar article, as shown and described.

JEAN R. SHREWSBURY.
